RADIO SHIELDING MEANS

Walter J. Spengler, Tullio Tognola, and Jakob R. Frei, Sidney, N. Y., assignors to Bendix Aviation Corporation, South Bend, Ind., a corporation of Delaware

Application May 1, 1939, Serial No. 271,220

7 Claims. (Cl. 174—72)

This invention relates to ignition apparatus and more particularly to radio shielding means for electrical apparatus, such as the ignition system of an internal combustion engine or the like, and methods of making the same.

One of the objects of the present invention is to provide novel radio shielding means for ignition conductors whereby the shielded portions of the latter are held against substantial movement, such as vibratory movement, relative to the shielding means.

Another object of the invention is to provide a novel method for constructing a radio shielded electrical conductor of the above character.

Still another object is to provide a novelly constructed radio shielding harness for the ignition distribution system of an internal combustion engine.

A further object is to provide a novel method for constructing a radio shielding harness of the above type.

A still further object is to provide a novel radio shielding harness for ignition conductors which is so constructed that said conductors may be readily installed therein without danger of damaging the insulation on said conductors.

Another object is to provide novel radio shielding apparatus for ignition conductors which is so constructed as to obviate the entrance and accumulation of moisture therein and to eliminate insulation failures.

Another object is to provide a novel radio shielding harness wherein the shielded ignition conductors will not be chafed or adversely affected in any way by reason of the vibration of the engine on which the harness is installed.

Still another object is to provide a radio shielding harness for an ignition distribution system having novel means associated with the manifold thereof for electrically connecting conductors in the manifold to detachable shielded conductors.

The above and further objects and novel features of the invention will more fully appear from the following detailed description when the same is read in connection with the accompanying drawings. It is to be expressly understood, however, that the drawings are for the purpose of illustration only and are not intended to define the limits of the invention, reference for this latter purpose being had primarily to the appended claims.

In the drawings wherein like reference characters refer to like parts throughout the several views,

Fig. 1 is an elevation view, partly in section and 55

with parts broken away, illustrating one form of shielding harness comprehended by the present invention;

Fig. 2 is a detail sectional view taken on line 5 2—2 of Fig. 1 and showing a socket connection associated with the harness manifold;

Fig. 3 is a detail sectional view taken on line 10 3—3 of Fig. 1;

Fig. 4 is a sectional elevation view of one form of the insulating sleeve which may be used in carrying out the invention, the section being taken on line 4—4 of Fig. 5;

Fig. 5 is an elevation view of said insulating sleeve as viewed from the left in Fig. 4;

Fig. 6 is a side elevation, partly in section and 15 with parts broken away, showing the harness of Fig. 1 connected to a magneto distributor shield;

Fig. 7 is a detail sectional view, with parts broken away, illustrating the shielding connections between the manifold and distributor shield;

Fig. 8 is a side elevation, partly in section and 20 with parts broken away, illustrating one manner of connecting a portion of the shielding harness to a spark plug;

Fig. 9 is a view similar to Fig. 2 showing the 25 socket plugged as it is during the operation of filling the manifold;

Fig. 10 is an elevation view illustrating a second embodiment of the invention;

Fig. 11 is a side elevation of the manifold of 30 Fig. 10;

Fig. 12 is a detail sectional view taken substantially on line 12—12 of Fig. 10;

Fig. 13 is a detail view of a socket portion 35 adapted for connection to the manifold tube of Fig. 10; and

Fig. 14 is a sectional view taken on line 14—14 of Fig. 13.

Two embodiments of the invention are illustrated in the drawings, by way of example, in 40 the form of shielding harnesses adapted for use on modern radial aircraft engines, but it will be understood that the novel features of the invention may be incorporated in shielding harnesses for other types and sizes of engines. Each form of harness shown comprises a metallic manifold connected by shielding leads to the radio shields on one or more magnetos or ignition distributors and having a plurality of outlets to which conduits for shielding individual conductors leading to the engine spark plugs are detachably connected. Each spark plug may be connected to a distributor terminal by means of a continuous conductor but preferably the spark plug leads are detachably connected to separate

conductors in the manifold of the harness at the outlets in the latter and, if desired, those portions of the ignition conductors between the main manifold tube and the magneto distributor may also be readily detachable.

In harnesses heretofore provided much difficulty has been experienced in getting the insulated conductors into the manifold of the harness, particularly without chafing the insulation thereon at points where the conductors must be pulled around sharp metallic corners. This initial chafing of the insulation on the conductors has been a serious source of electrical loss due to corona effect and of failures due to the ultimate complete breakdown of the insulation. In the embodiment shown in Figs. 1 to 8, inclusive, there is provided a novel manifold for an ignition harness which may be readily and systematically wired without the slightest danger of injury to the insulation on the conductors. The novel manifold is also so constructed that the wires or conductors therein may be readily inspected or replaced without completely rewiring the same as is necessary when a faulty conductor is embodied in harnesses of the types heretofore provided. Additionally, said novel manifold is stronger per unit of weight than prior types of manifolds having the same capacity.

In the form illustrated in Fig. 1 the novel manifold comprises a ring-like casting 15, the major portion of which is substantially channel- or U-shaped in radial cross-section (Fig. 3). The open face of said casting is interrupted at suitable intervals by integral cross pieces or lugs 16 to which suitable brackets 17 are secured, the latter serving as means for attaching the manifold to an engine (not shown). The openings between lugs 16 may be closed by removable plates 18 which may be either cast or stamped. The closure plates may be secured to ring 15 by any suitable means, such as set screws 19 which engage threaded bores in bosses 20 on the ring. In order to increase the strength and shielding properties of the assembled manifold, plates 18 are preferably provided with pilot portions 21 that closely fit the openings of ring 15. The latter and plates 18 are preferably cast from an aluminum alloy or other suitable light weight metal, thereby rendering it possible to provide relatively thick and strong wall sections without making the harness prohibitively heavy for aircraft use. Casting of the parts makes it possible to proportion the wall thicknesses or provide strengthening ribs to meet with the strength requirements at particular points depending on the engine upon which the same is to be used. If desired, suitable gaskets may be employed between plates 18 and ring 15 to further insure against the entrance of moisture.

In most shielding harnesses of the continuous conductor type in use today on aircraft engines, one of the usual sources of failure is the burning of the insulation on the high tension conductors at or near the spark plugs. When the insulation on a single wire is burned or a single conductor becomes otherwise defective it is usually necessary to remove the entire harness from the engine and often to completely overhaul the harness to find and replace the damaged wire. Accordingly, the present invention provides novel shielded spark plug leads which are completely detachable from the manifold of the harness and the conductors therein.

For the purpose of providing means whereby 75

detachable electric and shielding connections between manifold 15, 18 and the spark plugs of an engine may be employed, the manifold has a plurality of outlet sockets combined therewith in a novel manner for receiving a plug connector.

As shown, each of said sockets comprises a cylinder-like portion 22 (Figs. 2 and 6) cast as an integral part of the closed face of ring 15 and extending radially thereof. Socket portions 10 22 are each provided with an interiorly threaded opening 23 (Fig. 2) and have communication with the interior of ring 15, 18. Preferably a hard metal bushing 24, which need not be removed during overhaul or inspection of the harness, is 15 provided in opening 23 to thus prevent unnecessary wear on the threads in the soft metal of the manifold ring. Accordingly bushing 24 may be considered as an extension of socket portion 22 and, hence, as a part of the manifold.

20 Slidably fitting into each bushing 24 and a recess 25 in the inner wall of casting 15, 22 is a rigid electrical insulating sleeve or tube 26, said sleeve having a portion thereof cut away (Fig. 5) to provide a passage 27 for one of the plurality 25 of insulated conductors 28 in the manifold (Fig. 2). The edges of opening 21 are preferably rounded to obviate any chafing of the insulation on conductors 28 when the latter are pulled into the manifold. The end of each conductor extending into sleeve 26 extends partially through said sleeve and is held against withdrawal therefrom by a metallic washer or tip piece 29 secured to the conductor and engaging a shoulder 30 in the bore of the sleeve. The outer end of sleeve 26 serves as a socket for receiving the unshielded but insulated end of an insulated conductor 31 leading to an engine spark plug or other ignition device.

For shielding purposes, insulated wire 31 is 40 surrounded, for the most part, by a flexible metallic conduit 32 and a rigid metallic elbow 33 (Fig. 8). The ends of the insulated wire or conductor project from the shielding lead 32, 33 and are preferably surrounded by rigid insulating spacer sleeves 34 and 35 (Figs. 2 and 8) adapted to slidably fit into socket 22, 26 and the shielding barrel 36 of a shielded spark plug 37. Small coil springs 38 and 39 secured to the ends of conductors 31 in any well-known manner make 45 electrical contact between said conductors and the central electrodes 40 of spark plugs 37 and manifold conductors 28, respectively, or, if desired, said springs may be secured to electrodes 40 and conductors 28 for detachable contact 50 with conductors 31. The ends of shielding conduit 32 are preferably detachably connected to manifold bushing 24 and elbow 33 by any suitable means well-known in the art, such as by internally flanged nuts 41 and 42 (Fig. 1) that 55 cooperate with externally flanged ferrules secured to said conduit (Fig. 2). The free end of elbow 33 is also detachably secured to spark plug barrel 36 in the usual manner by means of a flanged nut 43. If desired, the adjacent ends of elbow 33 and conduit 32 may have telescopic relation and be soldered together as illustrated at 44 in Fig. 8.

Manifold 15, 18 may be connected to the conventional distributor shielding means 45 of one or more magnetos 46 (Fig. 6) by metallic shielding conduits 47 having sufficient capacity to house a conductor for each cylinder of the engine. In the form shown, each conduit 47 consists of a central rigid tube 48 and two flexible metallic tubes 49 and 50 which may be either detach-

ably or fixedly connected to the ends of said rigid tube in any desired manner. The free end of tube 50 is detachably connected by means of a nut 51 to an elbow 52 that is in turn associated with the distributor shields 45 for angular adjustment in a manner well understood in the art. The free end of flexible tube 49 may be detachably connected by a nut 53 to an outlet 54 cast integrally with ring 15. The flexible conduits 49 and 50, as well as conduits 32 referred to above, are preferably constituted by an inner corrugated metal tube having solid or continuous walls and an outer covering of braided metal strips.

The harness as above described may be successfully used for shielding a high tension ignition distribution system of an engine to prevent interference with radio reception by electrical and magnetic radiations therefrom but would be subject, in a lesser degree, to some of the same disadvantages inherent in harnesses heretofore provided. For example, the insulated conductors, particularly conductors 28 would be subjected in use to movement and rubbing action as a result of engine vibration, thereby causing chafing of the insulation and ultimate failure. Additionally, moisture resulting primarily from condensation within the shielding conduits would be apt to collect in the harness and on the insulated conductors, as it invariably does in harnesses now in use, thereby causing electrical losses and reduced efficiency.

To obviate the above disadvantages all or desired parts of the harness may be filled in accordance with the novel method of the present invention with novel means for precluding movement of the conductors relative to each other or to the shielding harness and for precluding either the entrance or condensation of moisture in the latter. The novel filler, in the form shown, is constituted by an electrical insulating material 55. One filling compound which has proved very successful in tests is composed of a cashew-nut-shell oil product such as polymerized cashew-nut-shell oil, made in accordance with the disclosures of U. S. Patents Nos. 1,725,797, 1,838,077 and others issued to Mortimer T. Harvey. This product in liquid form having a viscosity comparable to S. A. E. No. 250 oil is mixed with a small quantity of formaldehyde or other suitable drying agent and introduced into the desired parts of the harness in a manner hereinafter to appear. The filled parts are then placed in an oven and heated for several hours at a temperature of approximately 120 to 135° F. until the compound is dry throughout. The drying is actually brought about by chemical reaction but is accelerated by the application of heat. The dried compound, which is solid but of a resilient spongy nature, serves as an excellent dielectric. It is not sticky, and is not adversely affected by heat.

In assembling the main manifold 15, 18, heretofore described, each of the conductors 28 are drawn through a socket 22, 26 until tip piece 29 abuts against shoulder 30. The free ends of said conductors are then systematically arranged in casting 15 through the openings normally covered by plates 18 and directed out of said casting through one of the outlets 54. Temporary plugs 56 and springs 57, held in place by suitable cap nuts 58 (Fig. 9) are then inserted in sockets 22, 26 for holding tip pieces 29 against shoulders 30 and the liquid mixture of cashew-nut-shell oil compound and formaldehyde is poured through the open face of ring 15 and permitted to settle

until all void spaces in the manifold, except the portions of sockets 26 outwardly of tip pieces 29, are filled. Plates 18 are then secured in their places and the assembled manifold is baked as above described until the filling compound is dried by the chemical reaction of the cashew-nut-shell oil and formaldehyde.

Conductors 28 in the manifold will be firmly held against movement and further insulated by the dried insulating compound or matrix 55 and hence insure the greatest possible efficiency for an indefinite period of use without danger of injury to the insulation on the conductors and without necessity for replacement or overhaul. If it should prove desirable to overhaul the manifold or rewire the same for any reason, the molded compound 55 may be readily cleaned out of casting 15 by hand upon removal of plates 18 or the same may be dissolved by soaking the manifold in a suitable solvent, such as Sherwin-Wil- liams Reducer No. 90.

Preferably conductors 31 in the shielded leads between manifold 15, 18 and spark plugs 37 are also filled with compound 55. Since the flexible portion 32 of said shielding lead ordinarily consists of a corrugated metal conduit surrounded by a braided metallic cover, the liquid filling compound may be introduced into the lead by pressure or drawn in by applying a vacuum to one end thereof. If desired, the filler compound may extend into the rigid insulating sleeves 34 and 35 surrounding the projecting ends of conductors 31. Shielding conduits 47 may also be filled in the same manner as shielding leads 32, 33, but it may be desirable in some instances to merely tie the conductors therein together so that they will be readily removable from the conduit at any time. The magneto distributor shield 45, 52 may also be filled or lined with filler compound 55, particularly when multiple plug and socket connections are employed at each end of the conduits 47. One suitable connecting means of this type is disclosed in Roger F. Horton, U. S. Patent No. 2,275,762.

A second embodiment of the invention is illustrated in Figs. 10 to 14, inclusive, as comprising a thin-walled, ring-like manifold tube 60 made of brass or other suitable metallic material, said tube being substantially rectangular in radial cross-section. Sockets 61, corresponding to sockets 22 of Fig. 2 and adapted to receive the ends of spark plug leads 31, 32 in the same manner, are novelly secured to manifold tube 60. In the form shown, each of the sockets 61 comprises a tube-like metallic member 62 for slidably receiving an insulating sleeve 26. The lower end of member 62 is closed and the upper end thereof is externally threaded for cooperating with lock nut 41 on the spark plug lead. For the purpose of securing member 62 to manifold tube 60, the central portion of one side of the former is cut away to provide an opening 63 (Fig. 13) and a corresponding or complementary opening is cut in a side wall of the tube. The edges of said temporary openings are soldered or otherwise suitably secured together to thereby form a closed structure with the interior of socket members 62 in communication with the interior of tube 60 (Fig. 12). One or more outlets 64 corresponding to outlets 54 of Fig. 6 are similarly secured to tube 60 for the attachment of shielding conduits 47 which connect with the magneto distributor shield. Conductors 28 extend into and are held in place in socket insulators 26 in the same manner described above and emerge from outlets 64

into said shielded conduits 47. Just as in the first embodiment, the shielding and electrical connections between manifold 60, 61 and the spark plugs and the magneto or other source of current may either or both be detachable at either or both ends thereof.

In order to fill manifold 60, 61 with insulating compound, plugs 56 are placed in sockets 26, 62 in the manner above described and outlets 64 are effectively sealed by means of flexible rubber grommets of a type well-known in the art. The conductors emerging from outlets 64 extend through a plurality of openings in the grommets and the latter are pressed into firm engagement with each one of the wires and the outlets by means of nuts engaging the grommet and threaded portions of the outlets in a manner well understood in the art. Gaskets 65 may be provided between cap 58 and bushing 24 or socket portion 62, as the case may be, to insure an airtight connection. A source of vacuum is then connected to tube 60 at one or more openings 66 in any suitable manner and the filling compound 55 in liquid form is drawn in by the suction through one or more openings 67. Because of the evacuation of the manifold the filling compound seeks and fills all the voids around conductors 28 and insulating sleeves 26. Preferably the liquid compound is allowed to settle for a short time and then baked to accelerate the drying thereof. Holes 66 and 67 may be closed with suitable plugs but this is not absolutely necessary. If desired the filling compound in liquid form may be forced into the various parts of the harness including the manifold tube and shielding leads by pressure means. The harness may be mounted on an engine by means of brackets 68 secured to ring 60.

Heretofore much difficulty has been experienced in preventing flash-overs from terminal 39 to a grounded portion of the spark plug or shielding along a path between insulating sleeve 35 and insulating lining 36 in spark plug barrel 36 (Fig. 8). Flash-overs of this character are facilitated by the accumulation of moisture on the engaging surfaces of said sleeve and lining or by moisture absorbed thereby and a series of flash-overs is effective to burn and destroy these insulating parts. The present invention comprehends novel means for obviating the accumulation of moisture on said parts and to prevent flash-overs of the above nature without altering the other characteristics and advantages of the shielded system or parts thereof. Said means are constituted by a thin film of non-hardening moisture repellent insulating material (not shown), having the consistency of a heavy grease, spread over the outer surface of sleeve 35 before the same is inserted into its socket. This insulating material substantially fills the very small space between the sleeve and lining 36 and functions to exclude moisture from the surfaces thereof and to prevent creepage of high tension sparks along said surfaces. One insulating material which has been found suitable is known commercially as "Tite Seal," and consists of a mixture of castor oil and mica powder. Sleeves 34 (Fig. 2) may be similarly covered with said insulating material if desired.

There is thus provided novel means adapted for use in shielding the ignition distribution system of an internal combustion engine and a novel method for assembling the various parts thereof. A novel shielding harness is provided wherein the spark plug leads are wholly detachable from a

novelly constructed manifold and wherein the current carrying conductors are prevented from rubbing against each other or against the shielding surrounding the same during the operation and, hence, vibration of the engine on which the harness is mounted. Novel means are also provided whereby one or a plurality of encased conductors may be molded in a matrix of insulating material which may be removed either manually or by means of a solvent without destroying the casing therefor. The novel shielding means provided is relatively inexpensive to manufacture and the upkeep thereof is considerably less than harnesses heretofore provided since the major portion thereof will seldom if ever need to be overhauled. The harness provided is also safe and dependable particularly since it is absolutely impervious to moisture of any nature whatsoever.

Although only two embodiments of the invention have been illustrated and described by way of example, it is to be expressly understood that various changes might be made therein. For example, the manifold sockets for receiving the spark plug leads may have an end rather than a side thereof secured to the manifold tube and yet embody certain features of the invention. Various other changes in the design and arrangement of parts illustrated and in the materials suggested may be made without departing from the spirit and scope of the invention, as will now be apparent to those skilled in the art. For a definition of the limits of the invention, reference is had primarily to the appended claims.

What is claimed is:

1. A radio-shielding harness for the conductors of an ignition system comprising a rigid metallic manifold casing for enclosing and shielding at least a portion of each of a plurality of ignition conductors, and a unitary mass of solid dielectric material in a dry, non-moldable state substantially filling said casing around said conductors, said material being constituted by a dry reaction product of cashew-nut-shell oil and formaldehyde.

2. Shielding means for one or more electrical conductors comprising a metallic conduit having a continuous wall structure, and a solid dielectric material filling said conduit around said conductors, said material being constituted by a dry reaction product of cashew-nut-shell oil and a drying agent.

3. In a shielding harness, a metallic manifold casing for enclosing and shielding an electrical conductor, and a dry flexible dielectric filling said casing around said conductor, said dielectric being constituted by a solid reaction product of liquid cashew-nut-shell oil and formaldehyde.

4. The method of making a radio shielding harness which includes the steps of making a metallic casing, placing one or more electrical conductors therein, evacuating said casing, introducing a mixture comprising cashew-nut-shell oil and formaldehyde in liquid form into said casing around said conductors, and permitting said mixture to solidify.

5. In a radio shielded ignition system, a metallic casing, an electrical conductor having a terminal in said casing, an insulating sleeve surrounding said terminal and extending beyond the same, a second electrical conductor extending into said sleeve, a second insulating sleeve surrounding said second conductor in said first-named sleeve, and a film of non-hardening in-

sulating material of a plastic nature interposed between said sleeves.

6. In a radio-shielding harness for the insulated conductors of an ignition system of an internal combustion engine, a rigid metallic manifold casing containing and shielding at least a portion of each of a plurality of insulated conductors, radio-shielding means extending from said casing to the spark plugs of said engine for connecting the conductors in said casing to said spark plugs, and a yieldable solid dielectric material in a dry, non-moldable state substantially filling the space in said casing around said insulated conductors, said material being constituted by a reaction product of polymerized cashew-nut-shell oil and formaldehyde.

7. A radio-shielding harness for the conduc-

10 tors of an ignition distribution system of an internal combustion engine comprising a rigid metallic manifold conduit containing and shielding at least a portion of each of a plurality of insulated ignition conductors, a plurality of flexible radio-shielding conduits extending from said manifold conduit to the spark plugs of said engine, each of said flexible conduits containing at least a portion of an insulated conductor and a dry reaction product of polymerized cashew-nut-shell oil and formaldehyde substantially filling the remainder of the space therein for positioning and supporting the conductor or conductors surrounded thereby.
